UNITED STATES PATENT OFFICE.

STANLEY J. BENNER AND CLINTON V. J. DIEHL, OF HAZLETON, PENNSYLVANIA.

CHAIN LINK CONSTRUCTION.

Application filed January 13, 1921. Serial No. 436,921.

To all whom it may concern:

Be it known that we, STANLEY J. BENNER and CLINTON V. J. DIEHL, citizens of the United States, residing at Hazleton, in the county of Luzerne, State of Pennsylvania, have invented certain new and useful Improvements in Chain Link Constructions; and we do hereby declare the following to be a full, clear, and exact description of the invention, such as will enable others skilled in the art to which it appertains to make and use the same.

This invention relates to chain constructions, particularly to the link elements thereof and has for its object to generally conceive and improve the construction of the links and the manner of the assemblage thereof, eliminating the use of pins, cotter pins, bolts and other such securing elements heretofore necessary in chain construction.

A further object of the invention is to provide a chain of such character that any or all of the links thereof may be quickly and easily taken apart and assembled, without the use of any tools whatever, and which has its connecting elements so constructed and arranged that the strain upon the chain will be equally distributed to all parts of the links thereof and the wear upon the connecting elements is equally as evenly distributed.

With these and other objects in view, the invention consists in the novel construction, combination and arrangement of parts, all of which will be described more fully hereinafter, illustrated in the drawings, and particularly pointed out in the claims.

In the drawings:

Figure 1 is a side elevation of a portion of a chain construction in accordance with the invention.

Figure 2 is a top plan view of the chain.

Figure 3 is a transverse sectional view taken substantially upon line 3—3 of Figure 1.

Referring now more particularly to the drawings, 4 indicates the central or connecting link of the chain, while 5 indicates the side links thereof. The central link in the present instance is of solid or semi-solid construction, and is provided at its ends with laterally projecting studs 6, the studs upon the opposing sides of the link being alined with each other.

The studs 6 are of cylindrical shape, and

the side portions thereof are concaved as indicated at 7, the base and outer ends of the said studs being of equal diameter.

The side links 5 of the chain are each provided near their ends with longitudinally disposed slots as shown, the inner portions of which 8 are of such size as to permit the outer or head portions of the studs 6 to pass through, while the outer ends of the slots are of restricted width, such width being equal to the concave portions of the studs. It will be noted that the slots in the side links extend entirely through the latter, so that the studs 6 project entirely through the said links.

In assembling the chain links, the side links 5 are engaged with the studs 6 by passing the latter through the enlarged portions 8 thereof and then moving the side links 5 outwardly until the concave portions of the studs are confined between the restricted portions 9 of the said link slots. The links are therefore positively connected and are insured against becoming accidentally disengaged from each other, no pins or other securing elements heretofore employed being necessary in the attachment of the said links. Furthermore, by constructing the studs in the manner specified, it is obvious that the strain to which the chain links will be subjected will be borne by that part of the stud adjacent to the base, the outer or head end of the stud being relieved of such strain. It is further obvious that, while being securely held together, the links are free to move relative to each other, and will not hinder the operation of the machine with which the chain is used in passing around sprockets.

The enlarged intermediate portions of the connecting or intermediate links, as illustrated in the drawing, (particular reference being made to Figure 2) not only serve to increase the stock and hence the strength of these links, but terminally provide shoulders, arranged in the path of longitudinal movement of the side or connecting links when arranged in a position in alignment with the main or side links, to prevent accidental disengagement of the links in use, it being obvious that when it is desired to disconnect or uncouple two adjoining links it is necessary to dispose those links in relatively angular position, so that the adjacent shoulder of the enlargement on the connecting or intermediate link is disposed par-

- allel with the side edge of the main link, whereupon longitudinal movement of the pivot pin in the slot of the main link may be accomplished. In other words, the shoulders formed by the extremities of these enlargements, intermediate of the connecting links, constitute stops against relative movement of the adjacent links or members of the chain.
- 10 Furthermore, it will be observed that the entire length of the stud or pin projecting laterally from the intermediate or connecting link constitutes a bearing for the main or side link, there being no projection of said
- 15 pin or stud beyond the outer surface of the side link, and the concaving annularly of the stud or pin between the enlarged head and base thereof, in connection with the convexing of the seat at the end of the slot in the main or side link serves to position the side link definitely with relation to the connecting link and hold the connected links against relative lateral displacement or movement, so that uneven distribution of longitudinal
- 20 strain upon the chain is prevented and enlargement laterally of the main links is rendered unnecessary. This relative construction and mounting of the links prevents strain on the chain from being shifted to one side thereof as will occur in those constructions of chains where there is any possibility of relative lateral shifting of the links, due to wear either of the connecting stud or pin or of the sides of the links.
- 25 35 In the construction submitted the wearing of the adjacent side surfaces of two connected links, if they should be in contact, or if such wear should be due to the interposition of dust or foreign matter, will not affect the direction of strain on the chain or the position laterally of the said links. As a matter of fact, in the construction indicated, the wearing of the sides of the links when they overlap is prevented or at least minimized
- 30 40 45 and the efficiency of the chain remains normal and constant, regardless of the use thereof.
- Again, it will be obvious that any wearing of the contacting and relatively concaved and convexed surfaces of the stud or pin and the seat engaging the same will not affect the centering or the relative arrangement of those bearing surfaces, with reference to the line of strain applied to the chain, and will not tend therefore to change the lateral position of one link with relation to the other.
- 50 55 The cooperating and spherically rounded contacting surfaces of the pins and side links constitute what for convenience may be considered semi-ball and socket joints which, in addition to the advantages heretofore mentioned, involve in the wearing of the contacting surfaces a seating of the said links on the pins which increases instead of diminishing the transverse rigidity of the
- chain structure to prevent side lash and the consequent mounting of the sprocket teeth and the jumping of the sprocket wheels by the chain. This transverse rigidity or stability is such that the chain will operate and follow the sprocket wheels even with one or more of the side links broken or displaced, so that the chain at that point depends upon only one side link. The remaining or intact side link will hold the adjoining parts of the chain in proper relation to traverse the sprocket wheels effectively until the injury is discovered and the machinery stopped to permit of the substitution of a new link.
- 70 75 80 85 90 95 100 105 110 115 120 125 130
- The above is a description of the invention in its preferred form but it will be understood that variation in the shape and construction of the studs and slots, as well as the size and disposition thereof may be varied without departing from the spirit of the invention as defined by the claims.
- What is claimed is:
1. A chain having main side links and intermediate connecting links, pivotally united by pins or studs rigid with and extending laterally from the latter and through the former and mounted in seats in the former, said studs or pins having concaved side bearing surfaces bounded at their outer and inner ends by enlarged heads and bases and the seats in the main links being transversely convexed to fit and center with said concaved side surfaces of the studs or pins to thereby form semi-ball and socket joints and hold the links in a fixed position against relative lateral movement and side lash.
  2. A chain having main side links and intermediate connecting links, pivotally united by pins or studs rigid with and extending laterally from the latter and mounted in elongated or slotted seats in the former, said studs or pins extending entirely through the main links and having means for definitely positioning the latter to prevent the lateral displacement thereof in either direction with relation to the intermediate connecting links, said intermediate or connecting links being provided with shoulders to limit the relative longitudinal movement of the main or side links when arranged in an alinged relation, and the side links having rounded terminals for contact with said shoulders.
  3. A chain comprising alternate double and single solid link members, the former being provided with openings therethrough adjacent the opposite ends thereof and the latter being provided with integral oppositely projecting headed stud portions which are adapted to extend through said openings, and being also provided with integral shoulders adjacent the opposite end portions thereof with which the opposite ends of the

members of the double links are adapted to abut.

4. A chain comprising single and double links alternately arranged, the latter comprising oppositely disposed side members situated upon opposite sides of the single link members, the opposite ends of the members of each double link overlapping the opposing end portions of adjacent single links and each of the members of the said double links being provided with elongated openings in the opposite end portions thereof and the said single links each being provided with integral oppositely extending headed projections adjacent its opposite ends, which projections are adapted to extend through the said openings, and said single links each being provided with shoulders adjacent its opposite ends which are adapted to abut with the adjacent ends of the members of the double links, substantially as described.

5. A chain comprising single and double links alternately arranged, the members of each double link being situated upon opposite sides of and overlapping the adjacent

opposing ends of adjoining single links, and each double link member being provided with openings of key slot shape, the smaller portions of said openings being adjacent the ends of said members and the larger circular portions thereof constituting inner terminals of the said openings, and the said single links each being provided with integral projections situated adjacent the opposite ends thereof, which projections terminate in circular heads, which heads are adapted to be inserted through the circular portions of said slots, and the said single links being provided with shoulders which are adapted to abut the ends of the members of the double link members to prevent disconnection of the links from each other, substantially as described.

In testimony whereof, we affix our signatures, in the presence of two witnesses.
